[57] CLAIM

The ornamental design for a stackable poker chip holder, substantially as shown and described.

DESCRIPTION

FIG. 1 is a perspective view of a stackable poker chip holder showing my new design;

FIG. 2 is a plan view of the poker chip holder in FIG. 1;

FIG. 3 is a front elevational view of the poker chip holder in FIG. 1;

FIG. 4 is an end elevational view of the poker chip holder in FIG. 1;

FIG. 5 is a bottom elevational view of the poker chip holder in FIG. 1; and

FIG. 6 is a perspective view of the poker chip holder of FIG. 1 in stacked array.

The broken line showing of a holder is to show environment only.

TIPS.
